HIS ATTORNEYS.

UNITED STATES PATENT OFFICE

2,250,666

COMBINED LABEL, CAP LOOSENER, AND
AUXILIARY CONTAINERCharles Webb Godefroy, Clayton, Mo., assignor to
Godefroy Manufacturing Company, St. Louis,
Mo., a corporation of Missouri

Application October 31, 1938, Serial No. 237,911

5 Claims. (Cl. 215—46)

My invention relates to containers of the screw cap type and has for its principal object to combine in a single device, a label, means for loosening the screw cap and an auxiliary container for materials to be added to the contents of the main container.

The invention is particularly applicable to bottles for containing a liquid hair dye to which is added, before use, a capsule containing powdered material. It is obviously desirable to have such capsules secured in some way to the main container so as not to be lost. Screw caps are sometimes difficult to loosen from bottles and an object of the present invention is to provide a loosening means. A further object is to provide a conspicuous surface for descriptive or advertising matter taking the place of the usual paper label.

The invention consists principally in a metal strip having two body or label portions connected by a central perforated portion fitting under the screw cap, one of said label portions having in-turned flanges on its underside for slidably supporting a small container. The invention further consists in the label member or combined label, cap loosener and auxiliary container and in the parts and combinations and arrangements of parts hereinafter described and claimed.

In the accompanying drawing,

Fig. 1 is a front elevation of a bottle having 30 applied thereto a combined label, cap loosener and auxiliary container embodying my invention,

Fig. 2 is an end elevation of the upper portion of the bottle,

Fig. 3 is a sectional view on an enlarged scale 35 on the line 3—3 in Fig. 2,

Fig. 4 is a sectional view on an enlarged scale on the line 4—4 in Fig. 1,

Fig. 5 is a perspective view showing the auxiliary container partly exposed,

Fig. 6 is a sectional view similar to Fig. 3 showing a modification; and

Fig. 7 is a top plan view of a further modification.

In the drawing there is illustrated a glass or other bottle 1 whose neck 2 is threaded to receive a screw cap 3, there being a flat shoulder 4 at the bottom of said threaded neck 2. Mounted on said neck 2 against shoulder 4 is the perforated central connecting portion 5 of my label device A, the lower edge of the screw cap resting thereagainst. Projecting downwardly from said central portion are inclined strips 7 that generally follow the angle of inclination of the upper portion 8 of the bottle. The upper or outer sur-

faces of said strips furnish space for suitable descriptive or advertising matter 9.

One of said strips 7 has in-turned flanges 10 on its underside in which rest flanges 11 on the 5 upper edges of a metal or other container 12. The drawing illustrates capsules 13 in said container, such capsules being of the type containing powdered material to be added to the liquid portion of the hair dye.

10 In Fig. 6 is shown a modification in which the portion of the label under the screw cap has a roughened or corrugated upper surface 20 for increasing its friction grip on the screw cap.

In Fig. 7 is shown a modification wherein the 15 label member has a third strip 30 adapted to contain descriptive or advertising matter and to be bent down against one wide side of the bottle.

Obviously the screw cap may be loosened by twisting the label member A, as by raising one of 20 the strips and giving it a sharp jerk. It may be desirable to press on the top of the cap at the same time, so as to increase the friction grip between the cap and the label member. The capsules needed for addition to the liquid when the dye is to be used are permanently associated with the main bottle where they are always available when needed.

What I claim is:

1. A combined label and auxiliary container for 25 bottles having necks comprising a perforated portion for fitting over the neck of the bottle, a label portion projecting downwardly from said perforated portion and an auxiliary container secured to said label portion.

2. A combined label, cap loosener and auxiliary container for screw cap bottles having necks, comprising a perforated portion for fitting over the neck of the bottle, label portions extending downwardly, one of said label portions having in-turned flanges on its underside and an auxiliary 40 container having flanges cooperating with said in-turned label flanges.

3. In combination with a bottle having a threaded portion for receiving a screw cap and a flat shoulder at the bottom of said threaded portion, a screw cap on said threaded portion, a combined label, cap loosener and auxiliary container comprising a perforated portion fitting against said shoulder under said screw cap, downwardly extending label portions, one of said label portions having in-turned flanges on its underside and an auxiliary container having flanges cooperating with said label flanges.

4. In combination with a bottle having a polygonal body and a threaded neck portion for re-

ceiving a screw cap and a flat shoulder at the bottom of said threaded portion, a screw cap on said thereaded portion, a combined label, cap loosener and auxiliary container comprising a perforated portion fitting against said shoulder under said screw cap, a plurality of downwardly extending label portions each disposed over a face of said bottle, one of said label portions having inturned flanges on its underside and an auxiliary container having flanges cooperating with said label flanges.

5

5. A combined label, cap loosener and auxiliary container for screw cap bottles having necks, comprising a perforated portion for fitting over the neck of the bottle, the upper surface of said portion being roughened, label portions extending downwardly, one of said label portions having inturned flanges on its underside and an auxiliary container having flanges cooperating with said inturned label flanges.

CHARLES WEBB GODEFROY.
